Meyers, Cushman & Rea

UNITED STATES PATENT OFFICE.

THOMAS J. MALONEY, OF JERSEY CITY, NEW JERSEY, ASSIGNEE TO P. LORILLARD COMPANY, OF NEW YORK, N. Y., A CORPORATION OF NEW JERSEY.

SEALED-WRAPPED TOBACCO-PACKAGE.

1,247,697.

Specification of Letters Patent.

Patented Nov. 27, 1917.

Application filed May 7, 1917. Serial No. 166,832.

To all whom it may concern:

Be it known that I, THOMAS J. MALONEY, residing at Jersey City, in the county of Hudson and State of New Jersey, have invented certain new and useful Improvements in Sealed-Wrapped Tobacco-Packages, of which the following is a specification.

This invention relates to improvements in 10 tobacco or other packages, and pertains more particularly to packages of the sealed wrapped type.

To retain the original characteristics of 15 tobacco products—such as aroma, flavor, moisture, etc.—as far as practicable during the period between manufacture of the package contents and the sale to the customer, it is the custom to employ containers which tend to retain these characteristics 20 by rendering the package substantially air and moisture proof. In producing this result it is the practice to employ wrappers or wrapping elements which include, to a greater or less extent, the use of tin foil as 25 an essential feature, the characteristics of this material being such as to be particularly applicable for use in this connection. The cost of this material, however, under 30 present day conditions is high and the supply is more or less limited, due to various causes, factors which become of vital importance in connection with its use in the formation of containers for tobacco products, and especially where the packages are 35 sold to the consumer at low cost, as for instance, packages of smoking or chewing tobacco retailed at five or ten cents, the tobacco being shredded and adapted for pipe or cigarette use. The essential to the 40 consumer is the quality of the contents, but an essential factor to the manufacturer of the package is the cost of the container, any considerable advance in cost of materials necessarily reducing the already small margin of profit had in the production of the 45 packages. When, therefore, the cost of the essential tin foil is largely increased, it becomes a serious matter to the manufacturer, whose trade practically requires that the 50 standard of product be not impaired, necessitating that the air and moisture proof condition of the package be retained until the package reaches the hands of the consumer, a more or less indeterminate period.

55 Any substitute which may be employed

must not only practically preserve this air and moisture proof condition of the package, but in addition, the wrapped container must be capable of production within low cost limits, in order that the package may 60 retain its standard of content quality, be marketed at the standard price and yet permit of package manufacture at a profit.

Packages of this type are generally 65 formed to permit removal of contents from one end of the container, the latter generally being formed of a blank folded to the desired form and having one or both ends folded and tucked in and having the folded portions of the container countersunk at one or both ends, an arrangement which permits ready formation by machines which properly shape the container and, after filling, tuck in such ends, generally without the use of adhesive. The 70 sealing is generally provided by an external wrapper, which generally includes the tin foil material, variously formed, and provision is generally made for breaking the seal at the end through which the contents 75 are removed.

In the present invention the sealed wrapping is provided by two wrapper portions each folded into a more or less cup-shaped form and into which the opposite ends of 80 the container extend, the wrapper portions being arranged in either overlapping relation at their inner ends or in more or less abutting relation, such inner ends being overlapped by a strip, band, label, or stamp 85 adhesively connected to the two wrapped portions but practically free from such adhesive connection with the face of the container. Each wrapper portion may have an adhesive connection at the folds, but such 90 adhesive is not required to extend on to the container. The two cup-shaped portions, which are more or less duplicates of each other, practically inclose the container 95 when the label is in position, and as each cup-shaped portion is so folded as to produce a sealing effect, the wrapped container becomes a sealed package which will practically provide the air and moisture proof qualities heretofore obtainable by the use of 100 the tin foil material, these cup-shaped portions, however, being formed of a suitable paper which, in commercial practice, can be folded into cup-shape directly upon the container by suitable machines.

Not only do the cup-shaped portions provide such sealed wrapped condition, but the ends of the wrapper—the bottom of the cups of single thickness—positioned over and practically spaced from the countersunk tucked-in portions of the container provide an arrangement by which the sealed condition can be readily broken by any suitable implement or by a finger nail of the purchaser, the container forming a guide to permit this result to be obtained.

Since the paper wrapper is of considerably less cost than the tin foil, substitution can be had and yet preserve the desirable features of the sealed wrapped package and at the same time provide such package within the cost limits of the packages heretofore produced.

To these and other ends, therefore, the nature of which will be readily understood as the invention is hereinafter disclosed, said invention consists in the improved construction and combination of parts, herein-after more fully described, illustrated in the accompanying drawings, and more particularly pointed out in the appended claims.

In the accompanying drawings, in which similar reference characters indicate similar parts in each of the views:

30 Figure 1 is a perspective view showing one form of package falling within the principles of the present invention.

Fig. 2 is a similar view showing an end of the wrapper broken, a countersunk 35 tucked-in end of the container being opened to permit access to the interior of the container.

Fig. 3 is a view partly in section and partly in elevation taken through the container and showing the cups as having their inner ends overlapped.

Fig. 4 is a view partly in elevation and partly in section at right angles to Fig. 3.

Fig. 5 is a fragmentary detail showing the 45 wrapper ends as in abutting relation.

In the drawings, the container is shown at 10 being of a usual type of structure having its ends tucked in as at 11.

The wrapper, the thickness of which is 50 more or less exaggerated in the drawings, is formed of two sections or members 12 and 13, each section being formed from a blank into a cup-like formation, either by the use of a separate form or by the use of the container as a form, the latter being preferable, commercial machines being applicable for use in this connection, the folds being preferably positioned at the narrow sides of the package as indicated in Figs. 1, 2 and 4.

60 As shown in Figs. 3 and 4, this arrangement brings an intermediate portion of the blank into close fitting relation to an end of the container, thus producing a more or less close fitting cup at such end, the bottom 65 of the cup being of single thickness and the

skirt of the cup continuing inwardly into either an abutting or an overlapping or underlapping relation to the skirt of the cup extending inwardly from the opposite end of the container, Fig. 5 showing an abutting 70 relation while Figs. 3 and 4 show the arrangement in overlapping relation.

With the two cups in position, a strip-like element 14 is passed about the inner end arrangement of the two cups, and is 75 preferably adhesively connected to both cups, overlapping the cup joint. Element 14 may be a single member or a plurality of members in the form of a strip, a label, a band, or a revenue stamp as may be found 80 desirable.

As seen in Fig. 3, the particular manner in which the container ends are countersunk and tucked-in produces an annular container wall over which a single thickness 85 of the wrapper extends, thus producing a space between the container and the bottom of the cup. As will be readily understood, the single thickness of the cup bottom will permit of an easy rupture of such end, as indicated in Fig. 2, thus exposing the tucked in end of the container which is readily opened, thereby exposing the contents of the container without disturbing the connection between the cups. As a result, the 90 two cups may carry the desired advertising or printing matter which remains unaffected by the opening of the package.

As heretofore pointed out, the cups may be made separately and then applied to the 100 container or they may be formed directly on the container, this result being obtainable with machines now in commercial use which will permit the formation of the cup at one end after which the container is 105 simply shifted end for end and the uncapped end then presented to the mechanism to complete the formation of the second cup.

While I have shown the joint between the cups as located approximately midway of 110 the length of the package, it will be understood that the position of this may be varied as desired, thus producing cups of unequal dimensions.

As will be understood, the arrangement 115 provides for a sealed wrapped package with the wrapper of such a formation as will provide for the desired air and moisture proof conditions. And since the wrapper may be produced without the use of special machines, it will be understood that the substitution of the paper wrapper structure for the tin foil composite structure can be provided at minimum expense for changed machinery, and at a considerable decrease 120 in cost of material.

However, it will be obvious that, if desired the general features of the invention can be employed in connection with tin foil, the use of such foil in any of its forms in 130

producing the package, being considered as falling within the spirit and scope of the invention, when used either as a separate wrapper or as a portion of the structure of 5 the cup-shaped elements.

It is also to be understood that the invention is not limited to use in connection with tobacco products, it being obvious that it may be employed in connection with other 10 commodities adapted to be packaged, being especially adapted for use in connection with commodities where it is desired to provide a package of the sealed wrapped type, and I therefore desire it to be understood 15 that the invention contemplates its use outside of the field of tobacco products.

While I have shown and described a common form of fold for the cups, it will be understood that the invention contemplates 20 cup-shaped structure folded in other ways, the invention not lying in the particular form of fold but in the general features of the use of the more or less cup-shaped sections which have their inner ends overlapped by a suitable band adhesively connected to the sections but which requires no connection between the band and the 25 container.

While I have herein shown and described 30 a preferred way of carrying out the invention, it will be readily understood that changes and modifications therein may be required or desired to meet the various conditions of use, and I desire to be understood 35 as reserving the right to make any and all such changes as may be required or desired in so far as the same may fall within the spirit and scope of the invention as expressed in the accompanying claims.

40 Having thus described my invention, what I claim as new, is:—

1. In a sealed wrapped tobacco package, a container, a pair of cup-shaped wrapper sections formed from foldable material and 45 inclosing the opposite ends of the container, the section skirts closely fitting the side walls of the container and extending into juxtaposed relation, and means secured to said skirts and overlying the skirt ends for 50 retaining the sections in position and for completing the package sealing.

2. In a sealed wrapped tobacco package, a container, and means for inclosing the container, said means including a pair of 55 folded cup-shaped members into which the

opposite ends of the container extend, the skirts of said members closely fitting the side walls of the container and extending into juxtaposed relation to substantially inclose the container, and means secured to 60 and overlying member skirt ends for retaining the members in position and for completing the package sealing.

3. In a sealed wrapped tobacco package, a container, and means for inclosing the container, said means including a pair of folded cup-shaped paper members into which the opposite ends of the container extend, the skirts of said members closely fitting the side walls of the container and extending into juxtaposed relation to substantially inclose the container, and a strip-like element secured to and overlying member skirt ends for retaining the members in position 65 and for completing the package sealing. 70

4. In a sealed wrapped tobacco package, a container having a countersunk tucked-in end, and means for inclosing the container, said means including a cup-shaped member into which said container end extends with 80 a single thickness of the member overlying the countersunk end, and means for securing the member in position, whereby said tucked-in end may be exposed by rupturing the member portion overlying the counter- 85 sink with the walls of the latter forming a guide for the rupturing manipulation.

5. In a sealed wrapped tobacco package, a container having its opposite ends countersunk and tucked-in, and means for inclosing 90 said container to provide an air and moisture proof package, said means including a folded cup-shaped member into which one end of the container extends with the bottom of the cup-shaped member overlying 95 the tucked-in end of the container of single thickness, a folded cup-shaped member into which the opposite end of the container extends, the skirts of said members extending into juxtaposition to each other, and a strip-like element secured to said skirts and overlying the skirt ends, said element completing the package sealing. 100

In testimony whereof I have hereunto set my hand in the presence of two subscribing 105 witnesses.

THOMAS J. MALONEY.
